UNITED STATES PATENT OFFICE.

EDWIN O. KLEMM, OF SAGINAW, MICHIGAN, AND EDWIN W. SCHREIBER, OF YUMA, ARIZONA.

DESIGN FOR A COMBINATION STUDY-CHAIR.

47,464.

Specification for Design.

Patented June 15, 1915.

Application filed March 21, 1914. Serial No. 826,419. Term of patent 14 years.

To all whom it may concern:

Be it known that we, EDWIN O. KLEMM and EDWIN W. SCHREIBER, citizens of the United States, residing at Saginaw, in the county of Saginaw and State of Michigan, and Yuma, in the county of Yuma, State of Arizona, respectively, have invented a new, original, and ornamental Design for a Combination Study-Chair, of which the following is a specification, reference being had to the accompanying drawing, forming a part thereof.

Copies of this patent may be obtained for five cents each, by addressing the "Commissioner of Patents, Washington, D. C."

We claim:

The ornamental design for a combination study chair as shown.

EDWIN O. KLEMM.
EDWIN W. SCHREIBER.
